REVOLVING DOORLOCK

William Henery Tigue, Flint, Mich.

Application August 20, 1931. Serial No. 558,371
Renewed November 1, 1933

5 Claims. (Cl. 20—18)

This invention relates generally to means for locking revolving doors and similar structures, and particularly to a mechanism for locking a revolving door from a distance therefrom, together with means for unlocking the door at a distance therefrom, constituted by a new and novel arrangement and disposition of parts whereby the features of novelty and advantage set out below are attained.

10 It is an object of this invention to provide a simple, direct acting mechanism of this type, which is composed of few simple moving parts, and which is also easy to install and is inexpensive to manufacture.

15 It is also an object of this invention to provide a mechanism of the type described which is especially adapted for installation in banks, and other such public places, whereby in an emergency, a teller or other officer may prevent egress from the bank or the like by locking the revolving doors thereof, and at the same time giving a signal to police officers, guards, or the like persons, so as to bring aid needed in the emergency, the mechanism of the invention being easily incorporated in any bank or other electrical alarm system.

20 Another object of this invention is to provide a simple mechanism of the type described which is operated by means of electrically actuated magnets or motors.

25 These and other objects of the invention, its nature, and its composition and arrangement, and combination of parts will be readily understood by any one acquainted with the art to which the invention relates, upon consulting the following descriptions of the drawings, in which:—

30 Figure 1 is a top plan view of the device of the invention shown associated with a revolving door structure indicated in dotted lines.

35 Fig. 2 is a front elevational view of the operating mechanism.

40 Fig. 3 is a transverse vertical sectional view through that portion of the mechanism mounted upon the revolving door.

45 Fig. 4 is a sectional elevational view of the operating mechanism.

50 Fig. 5 is a transverse vertical sectional view through that part of the mechanism which is mounted upon the revolving door.

Fig. 6 is a perspective view of the upper slide of the operating mechanism.

Fig. 7 is a perspective view of the toothed lock and

Fig. 8 is a view of a signal light operating switch which is mounted upon the operating mechanism so as to light or extinguish signal lights according to the position of the upper slide thereof and

Fig. 9 is a diagrammatic view of the wiring system of the mechanism.

Referring in detail to the drawings, the numeral 5 generally designates the operating mechanism of the invention, which is mounted below the rotating door structure generally designated 6 in Fig. 1, which revolving door has a central shaft 7 on which is mounted a toothed wheel 8 secured for rotation freely thereon, which toothed wheel is segmentally cut out as indicated at 9 in equal radians, to form webs 10 between which are disposed coiled springs 11 for engaging either side of an upstanding lug 12 on a wheel 13 which is keyed as indicated at 14 to the shaft 7, so that there is a yielding connection between the toothed wheel 8 and the lug equipped wheel 13, so that as the toothed wheel 8 is rotated or is prevented from rotating, any shock upon the revolving door and other parts of the mechanism will be cushioned by the springs 11.

40 A suitable support 15 may be provided so as to carry the operating mechanism 5 in proper position as shown in Fig. 3. It will be obvious, that in order to lock the revolving door against rotation, the structure described above being connected thereto, it is only necessary to provide means to engage the toothed wheel 8 so as to prevent rotation thereof. Such a means is provided in the form of the operating mechanism generally designated 5. As seen in the drawings, the operating mechanism 5 consists of a base 16 of elongated form upon the outer end portions of which are mounted solenoid magnets 17 and 18 respectively.

45 On an intermediate portion of the base 16 between the magnets 17, 18 there is provided a guide 19 with a transverse passage 20 therethrough. Upon the upper surfaces of the guide 19 and at an opposite transverse side thereof are channeled members 21 which confine therebetween for long

itudinal movement a slide 22 which has ribs 23 projecting laterally into the channel defined by the guide 19 and the members 21 as better seen in Fig. 3. The slide 22 has enlarged portions 24 which accommodate vertically, set screws 25 for engaging the ends of magnetic cores 26 and 27 which have their inward ends introduced in bores 28 in the enlargements 24, the cores being slidable in the magnets 17, 18.

10 As illustrated in Fig. 6, the slide 22 has a horizontal portion provided with a diagonal slot 29. Slidable in the transverse passage 20 in the guide 19 is disposed the latch generally designated 30, which has at one side the teeth 31 for engaging 15 with the teeth 32 of the toothed wheel 8. A pin 33 rises from the upper surface of the latch and is slidably confined within said diagonal slot 29. The pin 33 is preferably arranged near the middle of the latch 30 and at one side of the latch's 20 longitudinal dead center.

When one of the electro-magnets 17, 18 is energized, the slide 22 will be drawn in the direction of the energized electro-magnet. Such a movement of the slide 22 causes the sides of its 25 diagonal slot 29 to work against the sides of the pin 33 on the toothed latch 30. Since the latch 30 can move only in a path transverse of the path of movement of the slide 22, the toothed end 31 of the latch will be moved in a direction toward 30 engagement with the teeth 32 on the wheel 8 or in a direction away from said wheel 8 depending upon which one of the electro-magnets 17, 18 is energized. Thus by energizing the proper one of the electro-magnets 17, 18 one may engage 35 the latch with the wheel and lock the same against rotation or withdraw the latch from the wheel so as to permit the wheel to rotate freely. The operation of the device may be arranged so that the latch will be in its initial position when 40 engaged with the wheel or when disengaged therefrom as may be convenient.

A suitable switch mechanism generally designated 34 may be mounted upon one of the stationary guide members 21 so as to be affected 45 by the movement of the slide 22, so that in one position of the slide the door will be free to rotate and a signal light will be maintained to indicate such position, and when the slide 22 is in the opposite position thereof, so as to lock the 50 revolving door against rotation, a light will indicate the presence of an emergency, said light being preferably located at a police station or other alarm center, so as to provide for notifying 55 of the existence of the emergency.

55 A method of wiring such an arrangement is indicated in Fig. 9. The solenoid 17 is connected to the power line or alarm circuit 35 which may lead to a police station and to a source of electrical energy, and a companion conductor 36 is broken by a switch 37 which may preferably 60 be located in a police station or other selected location, so that the lock may be withdrawn and the door permitted to rotate only when the device is operated by the switch 37 at the place designated.

The solenoid 18 has one side thereof connected to a switch 38 located in the bank teller's window or other place in the bank or the like public place, and to the power line 36, and the remaining side of the solenoid 18 is connected to the conductor 35. The base of the switch 34 is connected as indicated at 39 with the conductor 36, and the movable member of the switch is connected through a lamp 40 to the conductor 35.

65 The lamp 40 is provided to indicate both in

the bank and the police station or the like, that the door is open. Another contact of the switch 34 is connected thru a warning lamp 41 to the conductor 35 to give warning at the police station or in the bank or the like, that the door is closed and that an emergency exists. In one contemplated arrangement, the door can only be opened by the agency of the switch 37 in the police station, the switch 38 located within the bank or the like being effective only to lock the door, so that intruders cannot open the door.

80 It is believed that the above sufficiently describes the invention and the preferred embodiment thereof to enable any one acquainted with the art to which this invention relates to understand, make, and use the same, and accordingly further description is believed unnecessary.

85 It is to be definitely understood that I do not desire to limit the application of this invention to the particular modification set out herein, to 90 illustrate the principles thereof, and any change or changes may be made in material and structure and arrangement of parts, consistent with the spirit and scope of the invention.

95 Having thus described my invention, what I claim as new is:—

100 1. A distantly controlled lock means for a revolving door adapted to engage the door radially at any point in its rotation, said lock means comprising a stationary support, a projectable element thereon for engagement with a peripheral portion of the door, means on the support controllable from a distance for projecting and retracting the element, said peripheral portion comprising a rack yieldingly mounted on the 110 door for rotation therewith, said rack being adapted to be radially engaged by said projectable element for locking the door.

105 2. Remotely controllable electric lock means for a revolving door comprising, peripherally located radially engageable means carried by the door, and cushioning means connecting said engageable means with the door, and distantly controlled means for engaging the engageable means 115 radially locking the door against rotation.

110 3. A revolving door structure comprising a support, a rotating door carried by the support, a circular peripherally toothed member carried by the door, projectable means carried by the support for radially engaging the toothed member 125 for locking the door against rotation, yieldable means connecting the toothed member to the door for preventing damage to the door or to the projectable means comprising a rigid member fastened to the door, a plurality of springs carried by the rigid member and connected with said toothed member, said toothed member being rotatable relative to the door form except for the connection of the springs.

120 4. In a revolving door having a rack resiliently connected to said door for rotation therewith, a base supported adjacent one side of said door, a pair of spaced guides on said base, a detent slideable on said base between and positioned by said 130 guides, said detent having a portion engageable with said rack to lock the door against rotation, a pin projecting from said detent, a slide slidably resting on said pair of guides and having a diagonal slot receiving said pin, an armature 135 on each end of said slide, an electro-magnet on said base outward of each end of said slide, and in magnetic relation to said armatures, said electro-magnets being individually energizable to move said slide and withdraw said portion of 140

the detent from and project the same into locking engagement with said rack.

5. In a revolving door, a rack, means for resiliently connecting said rack to said door for rotation therewith, a base supported adjacent one side of said door, a pair of spaced guides on said base, a detent slidable on said base between and positioned by said guides, said detent having a portion engageable with said rack to lock the door against rotation, a pin projecting from said detent, a slide slidably resting on said pair of

guides and having a diagonal slot receiving said pin, an armature on each end of said slide, an electro-magnet on said base outward of each end of said slide and in magnetic relation to said armatures, said electro-magnets being individually energizable to move said slide and withdraw said portion of the detent from and project the same into locking engagement with said rack, said armatures being removably connected to said slide. 80
